UNITED STATES PATENT OFFICE

2,036,312

TOY RAILROAD TRACK AND ELECTRIC WIRE TERMINALS THEREFOR

Fred C. Ziesenhein, Girard, Pa., assignor, by
mesne assignments, to The Girard Manufacturing
Company, Girard, Pa., a corporation of
Pennsylvania

Application October 20, 1932, Serial No. 638,824

18 Claims. (Cl. 238—10)

My invention relates to improvements in toy railroad track and the like, and has particular reference to electric wire terminal means in association therewith.

Heretofore the electric wire terminals applied to toy railroad tracks have been mounted on a fibre base and involved the use of clip elements for engaging the rails. This terminal means of the prior art is not only expensive to manufacture, but the clip elements frequently get out of shape and fail to make a proper electrical contact with the rails. Furthermore, the clip elements are exposed, as are the wires, so that in the event that the toy train be derailed, the clip elements, which secure the wires, and which also engage the rails are likely to be injured or the wires pulled out.

It is, therefore, the primary object of my invention to provide a novel and improved terminal member which obviates the necessity of the fibre base with the attendant expense thereof and other objections heretofore noted.

It is an object of the invention to provide a novel terminal element which incorporates a shield element for carrying and protecting the terminal engaging element.

Another object of the invention is to provide a novel terminal element and rail construction whereby the terminal element will be gripped in place by a rail,—there being no clip elements exposed to be bent out of shape and result in faulty electrical contact with the rail.

The invention also resides in certain novel features of construction, combination and arrangement of the various parts, and in modes of use,—all of which will be readily apparent to those skilled in the art upon reference to the accompanying drawing in connection with the detailed description that follows.

In recognition of the requirements of the patent statutes I have illustrated in the accompanying drawing what appears to be a preferred example of the invention. However, it will be understood that the same is susceptible of considerable change and modification within the spirit and scope of the subject matter claimed hereinafter.

In the drawing, wherein the same reference characters have been used to designate the same parts in all views:—

Figure 1 is a top plan view of a straight section of track incorporating my novel electric wire terminal construction;

Figure 2 is a bottom plan view of a section of

track and illustrating two of my terminal elements associated therewith;

Figure 3 is a cross sectional view of a curved section of track to which the invention has been applied and which illustrates the terminal device in cross-section, and also shows the stepped tie construction so that the tread portions of the rails will be "banked", so to speak, to prevent the derailing of the train;

Figure 4 is an elevational view taken on the plane 4—4 of Figure 1, looking in the direction of the arrow;

Figure 5 is a perspective view of the novel terminal element detached.

Referring specifically to the drawing, numeral 15 6 denotes the tie elements of the straight track section illustrated in Figures 1 and 2 and which support the side and intermediate rails 8, 9,—there being the clip portions 7 engaging the base flanges x of the rails as usual.

The rails and ties are made out of sheet metal, as usual, although other forms of construction may be resorted to within the spirit and scope of the invention. Insulation 10 is adapted to insulate the third or intermediate rail 9 from 25 the ties 6, as indicated in Figures 1 and 3. The usual pin extensions 11 serve to connect adjacent track sections.

Coming now to the novel terminal element 12, illustrated in Figure 5, it will be noted that the 30 same comprehends an upstanding attaching flange or portion 13 whose bottom is laterally bent, as indicated at 13a. The portion 13a turns upwardly to provide the wall 14 which is spaced from and parallel to the wall or flange portion 35 13 so as to provide the groove 15, which is adapted to receive one base flange x of the track section 8 or 9,—the upstanding flange 13 being insertable into the slot y opening from the bottom of the rails between the base portions x. 40 Thus, the stock forming the two sides of the web portion of the rails 8, 9, embrace the flange 13 so as to make a good electrical contact.

In Figure 3 the rails are designated as at 8a, 45 9a—this depicting a curved instead of a straight section of track. The construction of the rails 8a, 9a, is, however, aside from the curvature the same as the construction of the rails 8, 9, of Figures 1, 2, and 4.

The wall or portion 14 of the terminal members 12 is shorter than the wall or flange 13, as clearly illustrated in Figures 3 and 5, and is bent laterally to provide the shield or contact-carrying portion 16 which carries at its under 50 55

surface the means for engaging and holding the circuit wire terminals.

Figure 5 illustrates very clearly that the clip plate 17, is disposed flatly against the under surface of the horizontal flange or portion 16 of the member 12 and is secured thereto by means of the rivet 18, or the like. It is to be noted, in this connection, that the rear end of the clip plate 17 is provided with an upstruck lug 17x which engages the adjacent end of the horizontal shield portion 16 so as to prevent the clip plate 17 from swinging relatively of the shield or portion 16. Therefore, the clip member or plate 17 will be held fast in position 15 by the simple expedient of the rivet 18 and the lug 17x.

The clip plate 17 is bent rearwardly, as indicated at 17a, to provide the clip portion 17b, whose intermediate portion is transversely 20 humped in the direction of shield 16. The portion 17b of the clip member 17 has a slot 20 at the site of the hump 17c,—which slot is adapted to receive the V-shaped tongue 19 which is formed integral with the clip plate 17. Thus, 25 a wire terminal 21 can be locked in place by the outward spring action of the clip portion 17b which draws the wire terminal against the apex of the portion 19,—all as illustrated in Figures 4 and 5.

30 The outer end of the portion 17b serves as a handle for moving such portion 17b toward the portion 17 when it is desired to pull the wire 21 out of engaged position, or when it is desired to insert a wire into the position shown in 35 Figure 5. The particular form of clip is not new and its operation is well known.

The tongue or member 19 need not necessarily be integral with the member 17, but may be attached and secured thereto, as for instance, 40 by the rivet or other fastening element 18.

The member 12 is preferably a stamping made from sheet metal, but obviously it may take the form of a casting, or be otherwise formed.

A special note is taken of the fact that the 45 clip-carrying and concealing shield 16 is disposed substantially below the plane of the upper edge of the flange or attaching portion 13 which goes into the slot between the sides which define the web of the rail. Thus, the 50 contact wires are disposed so that their terminals will be protected and concealed in the event that the locomotive should become derailed. Furthermore, the wires 21 are so disposed that they may readily be led out beneath 55 the rails, the insulation 21a on the wires serving to prevent the wires 21 from engaging the bases of the rails and producing a short circuit.

It will also be evident that the use of a terminal element 12, such as I have disclosed herein, will enable the track section to be moved without likelihood of loosening the terminals, as is the case where a fibre plate is used which engages the floor or sticks out laterally of the track so as to be prone to be knocked against as 60 the track sections are moved, or when the operator changes position in playing with the set.

In Figure 3 it will be noted that I have illustrated the ties 6a as provided with steps of increasing height so that the rails 8a will have 70 their tread portions located at different levels so as to provide a banked turn. The third rail 9a is supported on an intermediate step, while the outer rail 8a is supported on the higher step 23, the intermediate step being designated as at 22.

One important point to be noted is that should a car be derailed at the site of terminal carrier 12 and strike the flange 16 thereof, there will be a tendency to rock or bind flange 13 in slot y rather than to pull it therefrom. It is further to be noted that the contact-carrying guard plate 16, as shown in Figure 1, extends more than half way between the rails 8 and 9 and of course if desired it can be extended further toward the rail 8 than is shown. The 10 guard plate 16 therefore affords substantial protection for the wire 21a as indicated in Figs. 1 and 3 and likewise in Fig. 2.

It is believed that the novel features of construction and advantages thereof will be seen 15 readily from the foregoing description taken in connection with the accompanying drawing.

Having thus described my invention, what I claim as new and desire to secure by Letters Patent is:

1. The combination of a sheet metal toy railroad rail or the like bent to provide a tread, a base and doubled web portions, there being a slot 20 extending through said base portion and between the web portion sides, a wire terminal-carrying member having an upstanding flange insertable into said slot, and the sides of the doubled web portion of the rail yieldingly and frictionally engaging said flange portion to hold the same in place. 30

2. The combination of a sheet metal toy railroad rail or the like bent to provide a tread, a base and doubled web portion, there being a slot extending through said base portion and between the web portion sides, a wire terminal-carrying member having an upstanding flange insertable into said slot, the web portion sides yieldingly and frictionally engaging said flange portion to hold the same in place, said terminal-carrying member having a horizontal shield 40 portion below the level of the tread portion of the rail, and a terminal wire-engaging element carried beneath the shield portion. 35

3. A wire terminal carrier connection for electric toy rail road track and the like, comprising 45 a body providing a rail-carried portion, a laterally extending shield spaced clear of the rail carried portion and its rail, and wire terminal engaging means associated with said carrier body and disposed below and protected by said shield. 50

4. A wire terminal carrier connection for electric toy rail road track and the like, comprising a rail-carried portion, a laterally extending shield spaced clear of the rail carried portion and its rail, and wire terminal engaging means 55 carried by said shield at the under surface thereof.

5. A wire terminal carrier connection for electric toy rail road track and the like, comprising 60 a body providing a rail-carried portion, including a rail seat in part provided by said rail carried portion, a laterally extending shield spaced from said rail carried portion and carried by a wall of said seat, and wire terminal engaging means associated with said carrier body 65 and disposed below and protected by said shield.

6. A wire terminal carrier connection for electric toy rail road track and the like, comprising a body providing a rail-carried portion including 70 a rail seat having side walls, a rail-engaging holding member incorporated in said seat and providing one side wall thereof, a laterally extending shield carried by the other side wall of said seat, and wire terminal engaging means 75.

- associated with said carrier and disposed below and protected by said shield.
7. A wire terminal carrier for toy rail road track and the like, comprising a sheet metal blank bent to provide a flange insertable into a slot formed in a toy railway rail throughout its length and thereby securing the carrier to the rail, a rail seat for limiting insertion of the flange into a rail slot and having sides, one side 5 of said seat being provided by said flange and the other side of said seat being substantially parallel with said flange and terminating short of the plane of the top of said flange, said last-mentioned side having an outwardly projecting 10 shield, a leaf flatly contacting the bottom of said shield providing cooperating wire engaging portions, and securing means for said leaf comprising a single fastener on said shield and a lug on the leaf engaging an edge of the shield.
- 20 8. A wire terminal carrier for toy rail road track and the like, comprising a sheet metal blank bent to provide a flange insertable into a slot formed in a toy railway rail throughout its length and thereby securing the carrier to the rail, a rail seat for limiting insertion of the flange into a rail slot and having sides, one side 25 of said seat being provided by said flange and the other side of said seat being substantially parallel with said flange and terminating short of the plane of the top of said flange, said last-mentioned side having an outwardly projecting shield, and wire-carrying means on the lower side 30 of the shield.
9. The combination of a sheet metal toy railroad rail or the like having a slot opening upwardly through its base, a wire terminal member comprising a body having a flange portion insertable in said rail slot and adapted to be resiliently gripped thereby, a laterally extending wire carrying and protecting shield incorporated 35 in said body, the body being formed to provide a seat portion connecting said flange portion and shield, said seat portion being engageable with and receiving a portion of the rail base for limiting insertion of said flange portion into said slot, and said wire carrying and protecting shield extending away from said rail and below the plane 40 of the tread thereof.
10. The combination of a sheet metal toy railroad rail or the like having a slot opening upwardly through its base, and a wire terminal member having an attaching flange insertable in said rail slot and adapted to be resiliently gripped 45 thereby.
- 55 11. The combination of a sheet metal toy railroad rail or the like having a slot opening upwardly through its base, a wire terminal member having an attaching flange insertable in said rail slot and adapted to be resiliently gripped thereby, a shield flange on said member and projecting therefrom laterally of the attaching flange, and wire terminal holder means carried by and beneath said shield flange.
- 60 12. The combination of a sheet metal toy railroad rail or the like having a slot opening upwardly through its base, a wire terminal member having an attaching flange insertable in said

5 rail slot and adapted to be resiliently gripped thereby, a shield flange on said member and extending therefrom laterally of said attaching flange, and a wire terminal contact clip secured to the under face of said shield flange and covered thereby.

13. The combination of a sheet metal toy railroad rail or the like having a slot opening upwardly through its base, a wire terminal member having an attaching flange insertable in said rail slot and adapted to be resiliently gripped thereby, a rail base engageable seat provided in said member and formed in part by said attaching flange, and wire engaging means carried by said member at one side of said seat.

14. The combination of a sheet metal toy railroad rail or the like having a slot opening upwardly through its base, a wire terminal member having an attaching flange insertable in said rail slot and adapted to be resiliently gripped thereby, and said member extending laterally of the attaching flange beneath the rail to a point offset therefrom.

15. The combination of a sheet metal toy railroad rail or the like having a slot opening upwardly through its base, a wire terminal member having an attaching flange insertable in said rail slot and adapted to be resiliently gripped thereby, said flange having an extension projecting laterally therefrom, and wire terminal holder means connected to said extension at a point offset from the rail.

16. A connector for making detachable electrical connections to a sheet metal toy railroad track rail having a slot opening upwardly through its base, said connector including a short thin upright blade adapted to be inserted upwardly in said rail slot and to be resiliently gripped thereby, and an extension on said strip bent sidewardly therefrom to underlie the track rail.

17. The combination with a toy railroad track section, said section including a plurality of rails held in spaced parallel formation by ties, each of said rails being made of sheet metal bent downwardly to form a head portion and a double web portion, of a connector making electrical connection to one of the rails of said track, the said connector including a thin, short upright blade inserted upwardly from beneath the rail into the slit between the sides of the web of the rail and resiliently gripped thereby, and an extension extending from said blade sidewardly beneath the track section to a point outside the track section.

18. The combination with a toy railroad rail, said rail being made of sheet metal bent downwardly to form a head portion and a double web portion, of a connector making electrical connection to said rail, said connector including a thin, short upright blade inserted upwardly from beneath the rail into the slit between the sides of the web of the rail and resiliently gripped thereby, an extension on said strip bent sidewardly to a point offset from the rail, and a wire terminal holder connected to said extension.

FRED C. ZIESENHEIM.
